UNITED STATES PATENT OFFICE

2,413,563

ELECTRIC CIRCUIT INTERRUPTER AND
DISCONNECTING DEVICE

Benjamin R. Hermann, Lanesborough, Mass., assignor to General Electric Company, a corporation of New York

Original application December 13, 1941, Serial No. 422,901. Divided and this application June 14, 1943, Serial No. 490,824

6 Claims. (Cl. 200—114)

1

My invention relates to electric disconnecting devices and more particularly to a disconnecting device which may be readily interchangeable with a fuse device.

This application is a division of my application Serial No. 422,901, filed December 13, 1941, entitled Electric circuit interrupter and disconnecting device, and assigned to the same assignee as the present invention.

Many forms of fuse cutouts have been suggested heretofore for protecting electric circuits or controlling electric circuits. Devices of this sort commonly have a housing provided with a front opening with a cover hinged to the housing for closing this front opening. Usually a pair of terminals or contacts are mounted within the housing and the fuse tube is mounted on the cover and provided with contacts to engage the contacts or terminals in the housing when the cover is closed. Such cutouts are also provided with indicating means and, upon operation of the fuse device, movement of the fuse tube or of the cover or of both the cover and the fuse tube results.

My invention is concerned with an electric cutout and disconnecting device for interrupting larger blocks of power than such devices have been commonly used for heretofore.

Accordingly, it is an object of my invention to provide a new and improved cutout and disconnecting device combination for controlling larger blocks of power than such devices have commonly been used for heretofore.

A further object of my invention is to provide a new and improved cutout device which may readily be converted to a disconnecting device, which takes up a small amount of space, provides wide separation between the contacts, and gives an indication of the condition of the circuit while, at the same time, remaining protected against the weather, such as ice, snow, or rain.

Further objects and advantages of my invention will become apparent as the following description proceeds and the features of novelty which characterize my invention will be pointed out with particularity in the claims annexed to and forming a part of this specification.

For a better understanding of my invention, reference may be had to the accompanying drawings in which Fig. 1 is a side sectional view of my improved fuse cutout with the fuse intact and the cutout in the closed position, Fig. 2 is a view of the rear of the cover of the fuse cutout device shown in Fig. 1, Fig. 3 is an exploded view of a portion of the fuse cutout including the articu-

2

lated fuse link pull-out means of my invention, Fig. 4 is an enlarged sectional view taken on line 4—4 of Fig. 1, Fig. 5 is a side sectional view similar to Fig. 1 showing the disconnecting device of my invention in the closed circuit position, Fig. 6 is a view similar to Fig. 2 showing the rear of the cover including the disconnecting blade of Fig. 5, and Fig. 7 is a sectional view taken on line 7—7 of Fig. 5.

Referring now to the drawings, 10 indicates a housing or casing of porcelain or similar insulating material having an integrally formed electric creepage barrier 10' which separates two stationary terminal assemblies generally indicated at 11 and 12, respectively, mounted within housing 10. The upper and lower terminal assemblies 11 and 12, except for one additional part associated with the upper terminal assembly 11 and described hereinafter, are identical in construction and, accordingly, only the upper one of these terminal assemblies will be described in detail and the corresponding parts of the assemblies 11 and 12 will be designated by the same reference numerals. Terminal assembly 11 comprises a U-shaped terminal support 13 which is adapted to be cemented into a pair of pockets 14 in the housing 10, only one of which is visible in Fig. 1 since the other is immediately behind the one shown, which pockets are separated by a fin not discernible in the drawings but which are interconnected by means of an opening or notch in this separating fin. This interconnection is provided to facilitate the pouring of the cementing material, which is preferably poured hot through the lead entrance opening 16 in housing 10. By using a plurality of pockets into which the cementing material is poured, a stronger construction is provided than if U-shaped terminal supports 13 were cemented into a single large pocket in housing 10. Terminal assembly 11 further includes a terminal 17 shown in enlarged sectional view in Fig. 4 and described in greater detail hereinafter. An extension 18 on terminal 17 is provided so that terminal 17 may be rigidly supported by U-shaped terminal support 13 by means of bolt 19. The extension 18 is provided with lugs 20 to engage the edges of the U-shaped terminal support 13 so that the heavy lead coming through lead entrance opening 16 for engagement with terminal 17 will not cause the terminal to swivel about bolt 19 when the heavy lead is being formed or bent externally of the housing 10.

Terminal assembly 11 further includes a pair of U-shaped contact clips 21 which are electrically connected to extension 18 of terminal 17

through a ring-shaped contact 22, the contact clips being clamped to the extension 18 by bolt 19. In order to insure good contact at contact clips 21, I provide a plurality of spring strips 23 which are riveted as at 24 to U-shaped terminal support 13 and are arranged to provide spring backing means for contact clips 21. The upper terminal assembly 11 also includes a latch clip 25 which is riveted or fastened in any suitable manner thereto and the purpose of which will be set forth hereinafter.

The terminal 17 shown in enlarged sectional view in Fig. 4 includes a cylindrical lead-receiving portion or passageway 26. A long shoe 27 fits into the lead-receiving portion 26 and is adapted to be depressed into engagement with the lead, not shown, by means of a pair of screws 28 so as to clamp the lead between one wall of lead-receiving portion 26 and the shoe 27. Suitable means for preventing the screws 28 from being completely removed from the lead-receiving portion 26 may be provided. In order to hold the shoe 27 out of the way when putting a large lead into terminal-receiving portion 26, I provide retracting means comprising spring 29 which is connected to the shoe 27 by means of a guide pin 30, the lower end of which is spun over as shown at 31 into a depression 32 in shoe 27. A suitable washer 33 prevents the spring from dropping into the opening or aperture 34 in terminal-receiving portion 26, which opening 34 must necessarily be large enough to allow for angular displacement of pin 30. In order to permit spinning over of the end of pin 30, a suitable opening 35 is provided in the wall of lead-receiving portion 26 diametrically opposite the opening 34 for pin 30.

To the back of the housing or casing 10, there is secured a mounting bar 36 for attachment of the cutout to a suitable supporting structure, not shown. This mounting bar 36 is preferably cemented into an external recess 36' in the housing 10 in the same manner as are terminal supports 13.

In addition to terminal supports 13 and mounting bar 36, a pair of hinge supports 37 (Figs. 1, 5 and 7) are cemented into corresponding recesses 38 in the lower portion of housing 10, one on either side of the housing. These hinge supports 37, only one of which is visible in Fig. 1, each include a notch 39 within which suitable trunnions to be described hereinafter are mounted for pivotally supporting the door of housing 10.

In order to provide a closure for housing 10, I provide a cover or door 40, preferably made of a molded insulating compound or the like which includes an integral handle or eye 41 which may be either grasped manually or engaged by a suitable form of switch stick to open and close the cover 40 with respect to housing 10. Cover 40 is provided with a pair of recesses 42 only one of which is discernible in Fig. 1, since these recesses are in the same horizontal plane. The cover 40 is also provided with a barrier 43 which overlaps the creepage barrier 10' and thereby lessens the possibility of flashover between contacts by virtue of hot conducting gases passing therebetween, having an opening 44 therein which has sufficient clearance to accommodate a fuse tube 45 which may be of conventional construction having a pair of terminals or contacts 46 and 47 for engaging with the U-shaped contact clips 21. Mounted within fuse tube 45 is the conventional fuse link, preferably of the buttonhead type, which is held in position by cap 48 screwed to the upper part of fuse tube 45. As will be understood by those skilled in the art, the fuse link mounted

within fuse tube 45 includes a fusible element and a strain wire arranged in parallel with a flexible conductor connected to the lower terminal of the fusible element. In Fig. 1, only the flexible conductor 49 of the fuse link is visible which includes a plurality of cables in order to carry the high currents involved. As will be understood by those skilled in the art, the fuse including the fuse tube 45 and the fusible link, only the flexible conductor 49 of which is visible in Fig. 1, operates on the expulsion principle to interrupt the circuit therethrough.

The fuse tube 45 is supported on door 40 and is assembled with the door by thrusting the fuse tube 45 to which upper contact and cap 48 have been assembled through opening 44 in barrier 43. A pair of pins 50 integrally connected to upper fuse contact 46 are arranged to be inserted in the recesses 42 in cover 40 so as properly to position the fuse tube 45. Contact 47 which includes an opening 47' is then slipped over fuse tube 45 and the fuse tube is locked into position by means of fuse support 51 having an opening 51' therein which is slipped over the lower end of the fuse tube 45 and screwed to the cover 40 as at 52. By allowing a small amount of clearance between pins 50 and recesses 42 and between opening 44 in barrier 43 and fuse tube 45, the upper fuse contact 46 may be made slightly floating on cover 40 so as to line up properly with the contact clips 21 of upper terminal assembly 11 even when the cover 40 does not squarely seat in position on housing 10. Fuse support 51 having opening 51' therein for accommodating fuse tube 45 is provided with a pair of trunnions 53 for engaging the notches 39 in hinge supports 37, thereby providing a pivotal support for cover 40 and fuse tube 45.

Lower contact 47 is mounted on fuse tube support 51 by means of a pin 54 passing through trunnions 53. By allowing sufficient clearance between these parts, contact 47 may have a floating action relative to cover 40 so as to line up properly with contact clips 21 of lower terminal assembly 12. In order to prevent premature disengagement of the trunnions 53 from notches 39 when opening the door 40 of the fuse cutout, I provide on lower contact 47 a lug 56 which engages with the extension 18 of the lower terminal assembly 12 and effectively prevents such premature disengagement. Lug 56 is provided with a thumb screw 57 extending therethrough and having a substantially rectangular clamping shoe 58 mounted on the other end of the thumb screw for clamping the flexible conductor or cable 49 against projection 59 integrally associated with contact 47. In order to provide good electrical contact between contact clips 21 and contacts 46 and 47, each of the contacts 46 and 47 is provided with raised restricted contact surfaces 60 which are preferably formed of a metal, the oxide of which does not substantially interfere with the conduction of current. Silver, for example, is a suitable metal for such purpose since its oxide is relatively unstable physically, and consequently, raised restricted contacts of silver are very satisfactory although any other suitable metal may be used.

In order to provide prompt fuse link terminal separation in that range of fault current where there is not sufficient expulsion action caused by the arc in fuse tube 45, I provide an articulate fuse-link pull-out means which takes up a very small amount of space and yet which provides for a wide separation between the fuse-link terminals. This articulated fuse-link pull-out means

comprises a pair of rigid members or arms 61 and 62. Arm 61 has a forked portion 63 which is pivotally mounted to support 64 at 64. A suitable spring 65 associated with support 64 and shown in the exploded view of Fig. 3 is provided to bias arm 61 in a counterclockwise direction with reference to the view shown in Fig. 1 so as to tend to assume the dotted position shown. Arm 62 is provided with a drumlike portion 66 which houses a driving spring 67. This drumlike portion is pivotally mounted as at 68 to arm 61 with the spring 67 arranged to tend to cause clockwise rotation of arm 62 about pivot 68 with reference to Fig. 1. A suitable stop member 69 is provided on drum 66 of arm 62 to engage with a corresponding stop member 70 on arm 61 to limit the clockwise rotation of arm 62 about pivot 68 and cause arm 62 to assume the dotted position indicated in Fig. 1 when unrestrained by conductor 49. Arm 62 is provided with a forked end 71 to accommodate the conductor 49. When the fuse device of Fig. 1 is loaded, arm 62 is rotated in a counterclockwise direction with reference to arm 61 in the manner of a jack-knife moved to the closed position and arm 61 is rotated in a clockwise direction about pivot 64 with reference to the view of Fig. 1. Thereafter conductor 49 is passed within fork 71 and over drum 66, as best shown in Figs. 1 and 2, and is clamped between clamping shoe 58 and projection 59 so as to hold the articulated fuse-link pull-out means comprising arms 61 and 62 in the position indicated in Figs. 1 and 2. With the drum or spool-like portion 66 arranged over spring 67, molten metal contained in the arc blast expelled from the bottom of fuse tube 45 is prevented from injuring spring 67. Also, by virtue of the double arms 61 and 62, both of which are spring biased, the heavy cables making up conductor 49 are pulled from the end of fuse tube 45 at high speed. Since the forked portion 71 of arm 62 will tend to follow the conductor 49 rather than slide therealong upon blowing of the fuse, it follows that friction and binding are reduced to a minimum.

In view of the detailed description included above, the operation of my fuse cutout device will be obvious. As soon as the fusible section of the link melts, the strong spring pressure applied by springs 65 and 67 to arms 61 and 62, respectively, causes the remaining portion of the fuse link and particularly conductor 49 to be pulled quickly out of the tube 45 to insure rapid arc interruption even at low current. After operation of the fuse device, the arms 61 and 62 extend downwardly in the dotted position shown and serve as a very satisfactory indicating means to show clearly that the circuit is open. By use of such an articulated pull-out means, a sufficiently long operating stroke is obtained to pull the conductor 49 completely out of the fuse tube without requiring any large space within the cutout housing to accommodate the same in the unoperated position.

The fuse cutout described heretofore may readily be converted to a disconnect type of cutout by replacing door 40 with a door including a disconnecting blade as shown in Figs. 5, 6 and 7. The corresponding parts of the housing are identical with those shown in Figs. 1 to 4 and are, accordingly, designated by the same reference numerals. Referring now to Figs. 5, 6 and 7, I have indicated a disconnect cutout in which the housing 10 is closed by means of a door or closure member 72, preferably made of a molded insulating compound or the like, and including an integral handle or eye 73. In this respect, cover

72 is substantially identical with cover 40 of Fig. 1. Fastened to the lower inside portion of cover 72 as at 74 is a support 75 substantially identical with support 51 of Fig. 1 except that the support is slotted at 76 to permit pivoting of a disconnecting blade 77. Support 75 is provided with trunnions 78 identical with the trunnions 53 of Fig. 1 which are adapted to be mounted in the notches 39 of hinge supports 37. Blade 77 is pivotally mounted to support 75 by means of a pin 79 passing through trunnions 78. A suitable spring 80 is mounted in a recess 81 in the lower portion of blade 77 and presses against pin 79 to tend to bias blade 77 upwardly but to permit a downward movement of blade 77 for reasons enumerated hereinafter.

As in Fig. 1, in order to prevent premature disengagement of trunnions 78 from notches 39 of hinge supports 37, I provide an extension or projection 82 on disconnect blade 77 which is adapted to engage with the extension 18 of lower terminal assembly 12 so that, upon opening the door 72 of the disconnect cutout, disengagement of trunnions 78 and notches 39 cannot occur until a predetermined opening position of door 72 has been attained.

Disconnect blade 77 is preferably a solid conductor having spaced contacts 83 and 84 thereon for engaging with the respective upper and lower contact clips 21 of cutout housing 10. In order to insure good electrical contact, contacts 83 and 84 are preferably provided with raised restricted contact surfaces 85 similar to the contact surfaces 60 of Figs. 1 and 2.

In order to hold disconnect blade 77 in a parallel position with respect to door 72, I provide a knob 86 suitably fastened to door 72 and having an enlargement 87 thereon for cooperating with a notch 88 in the upper end of disconnect blade 77. As mentioned above, spring 81 tends to bias disconnect blade 77 in an upward direction to maintain the enlarged portion 87 of knob 86 in the latched or engaged position with respect to the notch 88 of disconnect blade 77. The disconnect cutout illustrated in Fig. 5 is not designed to open the circuit while the circuit is carrying full-load current but it will interrupt small currents such as a transformer exciting current. In order to prevent burning of the contact 85 and associated contact clips 21 under such conditions, disconnecting blade 77 is provided with an arcing tip 89 at the upper end thereof.

When the circuit is to remain disconnected for a time, the conducting disconnect blade 77 may be moved downwardly upon bodily removal of door 72 from housing 10 against the compression of spring 81 to unlatch notch 88 from knob 86 and blade 77 may be pivoted to hang downwardly in the dotted position shown in Fig. 5 and the door 72 may be reclosed to prevent snow and ice from entering the housing 10. The disconnecting blade hanging downwardly in the dotted position shown will provide a suitable indication that the circuit through the cutout is open.

The contact clips 21 engaging with contacts 83 and 84 maintain the blade and consequently the disconnect door 72 in the closed position when the cutout is arranged for carrying current. However, in order to hold the cutout in the closed position when the disconnect blade 77 is rotated to the dotted position shown and contact clips 21 no longer engage with contacts 83 and 84, I provide contact clip 25 associated with terminal assembly 11 in housing 10 for engaging the enlargement 87 of knob 86 and insuring that cover

72 remains in the closed position under such conditions.

The operation of the indicating disconnect cut-out illustrated in Figs. 5, 6 and 7 will be obvious in view of the detailed description included above.

While I have shown and described what I at present consider the preferred embodiment of my invention, it will be obvious to those skilled in the art that various changes and modifications may be made without departing from my invention, and I therefore aim in the appended claims to cover all such changes and modifications as fall within the true spirit and scope of my invention.

What I claim as new and desire to secure by Letters Patent of the United States is:

1. In an electric disconnect device, the combination of a housing, a door for closing an open side of said housing, spaced contacts in said housing, a support mounted on said door for relating said door to said housing, a rigid electrical conductor pivotally mounted on said support for interconnecting said contacts in said housing, and means for alternatively supporting said conductor on said support on said door in a position electrically isolated from at least one of said contacts and depending from the bottom of said housing to indicate an open-circuit condition between the contacts in said housing even though the open side of said housing is closed by said door.

2. In an electric disconnect device, the combination of a housing, a door for closing an open side of said housing, spaced contacts mounted in said housing, a rigid electrical conductor pivotally supported from one end of said door, latching means for the other end of said conductor for holding said conductor in substantially parallel relationship with said door, said conductor being so positioned with respect to said door and said housing as to complete an electric circuit between said contacts in said housing when the open side of said housing is closed by said door, and means for alternatively supporting said conductor from said door in a position electrically isolated from at least one of said contacts and depending from said housing to indicate an open-circuit condition between the contacts in said housing.

3. In an electric disconnect device, the combination of a housing, a door for closing an open side of said housing, spaced contacts mounted in said housing, a rigid electrical conductor pivotally supported at one end of said door, latching means for the other end of said conductor for holding said conductor in substantially parallel relationship with said door, means associated with the pivotally supported end of said conductor for causing said latching means to be operative, said conductor being so positioned with respect to said door and said housing as to complete an electric circuit between said contacts in said housing when the open side of said housing is closed by said door, and means for al-

ternatively supporting said conductor from said door in a position electrically isolated from at least one of said contacts and depending from said housing to indicate an open-circuit condition between the contacts in said housing.

4. In an electric disconnect device, the combination of a housing, a door for closing an open side of said housing, spaced contacts mounted in said housing, a rigid electrical conductor pivotally supported at one end of said door, latching means for the other end of said conductor for holding said conductor in substantially parallel relationship with said door, means including a spring associated with the pivotally supported end of said conductor for causing said latching means to be operative, said conductor being so positioned with respect to said door and said housing as to complete an electric circuit between said contacts in said housing when the open side of said housing is closed by said door, and means for alternatively supporting said conductor from said door in a position electrically isolated from at least one of said contacts and depending from said housing to indicate an open-circuit condition between the contacts in said housing.

5. In an electric disconnect device, the combination of a housing, a door for closing an open side of said housing, spaced contact assemblies in said housing, a pair of hinge supports having trunnion-receiving notches therein supported in said housing, a member mounted at one end of said door and having a pair of trunnions thereon for pivotally supporting said door to said casing when said trunnions engage said trunnion-receiving notches, a rigid electrical conductor pivotally mounted on said member for interconnecting said contacts in said housing when said trunnions engage trunnion-receiving notches and said door closes the open side of said housing, a lug associated with said conductor for engaging with one of said contact assemblies to prevent premature disengagement of said trunnions from said trunnion-receiving notches upon opening of said door, and means for alternatively supporting said conductor in a position electrically isolated from at least one of said contact assemblies and depending from the bottom of said housing to indicate an open-circuit condition between the contact assemblies in said housing.

6. In an electrical switching device, the combination comprising a housing, a door for closing an open side of said housing, spaced contacts mounted in said housing, an electrical conducting means pivotally mounted on said door and arranged to complete the electrical circuit between said contacts in said housing when said door is in the closed position, and means including said electrical conducting means for extending outwardly from said housing under open circuit conditions of said switching device when said door closes the open side of said housing to indicate the condition of said switching device.

BENJAMIN R. HERMANN.
